(57)

CLAIM

The ornamental design for a bottle, as shown and described.

DESCRIPTION

FIG. 1 is a front elevational view of the bottle showing our new design, the rear elevational view being the mirror image thereof;

FIG. 2 is a right side elevational view thereof, the left side elevational view being the mirror image thereof;

FIG. 3 is a bottom plan view thereof; and,

FIG. 4 is a bottom perspective view thereof.

The dash-dash broken lines are included for the purpose of illustrating environmental subject matter and form no part of the claimed design. The dot-dash broken line(s) define the bounds of the claimed design and form no part thereof.

1 Claim, 2 Drawing Sheets
